PROPORTIONAL ODORIZER

Edward Rolle, San Francisco, Calif., assignor to
Standard Oil Company of California, San Francisco, Calif., a corporation of Delaware

Application August 13, 1934, Serial No. 739,708

2 Claims. (Cl. 261—76)

This invention relates to devices for introducing a liquid into a confined flowing stream of a gas so as to impart to the latter a distinctive and easily recognizable odor, and particularly relates to a device of this character that will feed the said liquid at a rate substantially proportional to the rate of gas flow.

Heretofore apparatus of this type have involved intricate and complicated systems of floats, orifices, weirs, pumps and the like, all of which are susceptible to possible corrosive action by the liquid or gas being handled. Furthermore they are usually expensive to build and maintain, and a possible failure might have disastrous consequences, particularly where a normally odorless gas, such as that from natural gas wells, is to be odorized to reveal the presence of leaks, accidentally extinguished burners and the like.

It is an object of this invention to provide an odorizer that has no moving parts, that will operate with only occasional inspection or checking, that will feed the odorant liquid at a rate substantially proportional to the rate of gas flow over wide variations in the latter, and that will operate satisfactorily on a very small differential pressure in the gas line, such as would be caused by a partially closed gate valve, for example.

Another object is to provide an apparatus of this type that will be simple enough to be adjusted and tested by unskilled labor, and in which the continuity and correctness of operation may be determined quickly by a visual inspection, and without interfering with those forces tending to cause the flow of odorant liquid through its control means.

Another object is to provide an apparatus of this type which is economically and readily fabricated and installed from available standard parts.

These and other objects and advantages will become apparent from the description which follows and from the accompanying diagrammatic drawing, which forms a part of this specification and illustrates a preferred embodiment of the invention.

In the drawing the numeral 1 represents a gas line or conduit in which the direction of flow is indicated by the arrow. In the gas line 1 is an orifice plate or other differential pressure producing restriction 2 such as a partially closed valve. Pressure connections or conduits 3 and 4 with conventional block valves 5 and 6 lead off from line 1 above and below the restriction 2, as shown. The higher pressure or upstream line 3 leads to the gas space of a closed storage tank 7,

mounted several feet above the gas line 1 and which is adapted to contain the odorant liquid. Tank 7 is preferably horizontal so that the slight variation in liquid head as the liquid is withdrawn will have relatively little effect on the operation of the device. A gage glass 9 may be provided to indicate the liquid level.

The liquid outlet conduit 10 from tank 7 leads through a throttling type valve 11, which may be a needle valve, to the top of a sight glass 12, similar in form to a conventional drip type lubricator. Liquid outlet conduit 13 leads from the bottom of sight glass 12 through a valve 14, which is preferably of the quick closing type, to the lower pressure or downstream connection 4, through which latter the odorant liquid may enter gas line 1. A bypass conduit 15 from the top of sight glass 12 connects with liquid outlet 13 below valve 14, for a purpose which will be described below. Another bypass conduit 16, fitted with a throttling type valve 17 is provided between higher pressure line 3 and lower pressure line 4 below the apparatus just described, as shown.

During the installation of this equipment, it is desirable to calibrate the sight glass 12 and that part of the liquid outlet 13 between it and the valve 14. This may be done by closing valve 14 and filling sight glass 12 and the conduit therebetween with liquid from a graduate until a definite identifiable level appears in glass 12. This value is preferably converted into units of 1/1000 gallon, and will be utilized in a manner to be described below.

To place the device in operation, the tank 7 is filled with the desired odorant liquid 8. Valves 5, 6, and 11 are opened and valve 14 and 17 are closed. A time is chosen when the gas flow in line 1 is substantially low or at a minimum, as indicated by the usual gas metering equipment (not shown) in the line 1. From this value of gas flow, expressed in millions of cubic feet per unit of time, the throttle valve 11 is adjusted until the rate of odorant liquid flow into sight glass 12, as previously determined from the calibration above mentioned, reaches the desired value, which may be 1 to 3 gallons of odorant per million cubic feet of gas.

In making this calibration, after the sight glass 12 and the line 13 down to valve 14 has become filled, and the elapsed time noted, valve 14 may be quickly opened, allowing the accumulated quantity of odorant to flow into gas line 1, where it will be evaporated or otherwise absorbed by the gas flowing therein. As soon as

the desired setting of throttle valve 11 has been determined, as just outlined, valve 14 is opened and allowed to remain so, thus permitting the liquid to flow continuously out of glass 12, as fast as it accumulates therein. Valve 17 is so far permitted to remain closed.

The next step in the adjustment is preferably made when the gas flow in line 1 is substantially high or at a maximum. It will then be found, upon closing valve 14 and determining the time for sight glass 12 to fill to the calibrated point, that the rate of odorant flow will be much higher than its chosen proper proportional value for the high gas flow rate. Throttle valve 17 in bypass 16 is then slowly opened, reducing the differential available to cause odorant to flow through valve 11, until the flow of odorant, as determined by the calibrated sight glass 12 and valve 14, has been reduced to the desired proportional value. Thus with the throttle valve 11, the odorant feed rate may be adjusted as desired at a time the gas flow is at a minimum, and with throttle valve 17, the odorant feed rate may be adjusted to the same value at a time when the gas flow rate is maximum. The odorant flow rate at intermediate gas rates will be found to be substantially proportional thereto, at least within the range of practical and effective operation. Bypass 15 will permit the momentary stopping of the liquid flow into line 1, and its accumulation in sight glass 12, for the calibration and adjustments outlined without interfering with the differential pressure forces normally acting upon the flow of liquid through valve 11 from tank 7. Although a specific example embodying this invention has been illustrated and described, it is to be understood that modifications and changes could be made without departing therefrom, consequently all such devices as fall within the scope of the appended claims are embraced thereby.

I claim:

1. Apparatus for feeding a liquid into a con-

fined stream of gas, comprising a conduit for said gas, flow restriction means in said conduit for producing a pressure differential therein, a liquid storage tank, a pressure conduit leading from said gas conduit at a point above said restriction into said tank at a point above the liquid level therein, a liquid outlet conduit leading from said tank into said gas conduit below said restriction, a valve in said liquid outlet conduit adapted to control the rate of liquid flowing therethrough when the pressure differential is at a minimum, a sight feed means in said liquid outlet conduit, a bypass conduit connecting said pressure conduit and said liquid outlet conduit at a point below the flow control valve in said last named conduit, and a valve in said bypass adapted to control the rate of liquid flowing into said gas conduit when the pressure differential therein is at a maximum.

2. Apparatus for feeding a liquid into a confined stream of gas, comprising a conduit for said gas, flow restriction means in said conduit for producing a pressure differential therein, a liquid storage tank, a pressure conduit leading from said gas conduit at a point above said restriction into said tank, a liquid outlet conduit leading from said tank into said gas conduit below said restriction, a valve in said liquid outlet conduit adapted to control the rate of liquid flowing therethrough when the pressure differential is at a minimum, a by-pass conduit connecting said pressure conduit and said liquid outlet conduit at a point below the flow control valve in said last named conduit, a valve in said bypass adapted to control the rate of liquid flowing into said gas conduit when the pressure differential therein is at a maximum, and a means in said liquid outlet conduit for calibrating said flow control means, said means comprising a sight glass, a valve in the outlet from said sight glass and a bypass for said sight glass and said last named valve.

EDWARD ROLLE.
